UNITED STATES PATENT OFFICE.

WILLIAM L. OWEN, OF NEW ORLEANS, LOUISIANA.

ROLLER-SHADE HANGER.

Application filed February 12, 1926. Serial No. 87,817.

The invention relates to new and useful improvements in roller shade hangers, and more particularly to a roller shade hanger which is adjustable so as to accommodate window casings of different widths, and also roller shades of different lengths.

An object of the invention is to provide a roller shade hanger which is very simple in construction, and which can be cheaply made of sheet metal without the use of rivets, screws or the like.

A further object of the invention is to provide a sheet metal roller shade hanger wherein the supporting brackets for the roller shade are attached to the supports therefor merely by a cutting and shaping of the material in the making of the parts, thus providing a construction wherein the parts can be readily assembled when the hanger is attached to the window casing.

A further object of the invention is to provide a roller shade hanger of the above type, wherein the brackets for supporting the roller shade can be adjusted toward and from each other for different lengths of roller shades.

These and other objects will in part be obvious and will in part be hereinafter more fully disclosed.

In the drawings which show by way of illustration one embodiment of the invention—

Figure 1 is a perspective view showing more or less diagrammatically a window casing frame with my improved roller shade hanger applied thereto;

Fig. 2 is a front view on an enlarged scale of one of the hangers showing the same applied to the window casing;

Fig. 3 is a sectional view on the line 3—3 of Fig. 2;

Fig. 4 is a sectional view on the line 4—4 of Fig. 2; and

Fig. 5 is a perspective view of a portion of the supporting bracket for the roller shade.

The invention is directed broadly to a roller shade hanger which is very simple in construction and which can be cheaply made. The hanger consists of two members, one for each end of the roller shade, and each hanger consists of two parts, a supporting member and a bracket which is adjustably mounted thereon for supporting the end of the roller shade. These parts are made of sheet metal, and are made by cutting and stamping so that they are very cheaply made. The supporting part of the hanger is adapted to be attached

to the window casing by suitable securing means passing through the perforations in the ends thereof. This support intermediate its end is offset from the casing and is provided with slots at the upper and lower edges thereof. The hanger proper is also formed of sheet metal. The sheet metal is cut so as to form two laterally projecting lugs, and also to provide a recess which is adapted to receive the offset portion of the support. This sheet metal hanger has a slot formed therein at the upper end of this recess. The slot is located at the inner side of the recess, and close to the laterally projecting lugs. This slot in the hanger is adapted to engage the upper edge of the support in one of the slots thereof. The lower edge of the recessed portion of the hanger engages a corresponding lower slot in the support, and the lugs bear against the outside face of the support. These lugs prevent the hanger from swinging side-wise on the support, and thus a very rigid support is provided for the roller shade. The hanger can be shifted from one of said notches to another.

Referring more in detail to the drawings, my improved roller shade hanger consists of two supporting members and a cooperating bracket for each member. These supporting members are attached to opposite sides of the window casing. They are alike in construction, and a description of one will answer for the other. The window casing is indicated at 1 in the drawings, and the roller shade is indicated at 2. The hanger consists of a supporting member 3 which is made of sheet metal. This supporting member 3 is adapted to be secured to the window casing 1 by suitable screws or other securing devices 4, 4 which pass through perforations in the ends of the support 3. The support intermediate the ends thereof is provided with an offset portion 5. This offset portion 5 is provided with a series of slots 6, 6 and 7, 7. The slots are arranged in pairs, and are one above the other. A bracket 8 is adapted to be mounted upon this support 3 and the roller shade is mounted in these brackets at the opposite sides of the window casing. The bracket 8 is formed of sheet metal. Said sheet metal part has an upper horizontal edge 9, an inner vertical edge 10, and a front inclined edge 11. The bracket may be otherwise shaped without departing from the spirit of the invention. The body portion of the bracket 8 is cut along the lines 12 and 13 so

as to form lugs 14 and 15. The metal is cut so as to provide independent lugs, and one is turned one way, while the other is turned the other way, as clearly shown in Fig. 3 of the drawings. The body portion 8 of the supporting bracket is also formed with a slot 16. This slot 16 is of such width as to receive the offset portion 5 of the support. The distance between the lines of cut 12 and 13 in 10 the bracket 8 is less than the distance between the bottom edges of the slots 6 and 7. Therefore, the bracket is tilted upward at its outer end when it is placed over the support in the attaching of the same to the support, 15 until the slot 16 is brought into engagement with the slot 6. This allows the rear edge 10 of the bracket to be inserted in the slot 7, and the bracket then turned to the position shown in Fig. 4. When in this position, the 20 lugs 14 and 15 engage the outer face of the offset portion 5 of the supporting member 3. When thus placed on the support, the hook-shaped portion between the slot 16 and the inner face 10 of the bracket engages the 25 rear side of the offset portion 5 and thus prevents the bracket from turning through the weight of the shade carried thereby. The lugs prevent the bracket 8 from swinging laterally on the support, and the notches in 30 the support prevent the bracket from sliding laterally thereon. One of the brackets is provided with a perforation 17 and the other with an open end slot 18. These are of the usual construction for receiving the roller 35 shade.

It will be apparent that the supports for the roller shade may be attached to the window casing, without any particular accuracy in the placing of the same, after which the 40 brackets are placed in the supports so as to accommodate a shade of the length that it is desired to support. That is to say, the brackets are shifted laterally until they are properly positioned for the shade. 45 From the above it will be apparent that I have provided a very simple roller shade support, which can be made of sheet metal. It will also be understood that the parts may be readily assembled without any riveting of the 50 same together, and the parts may be readily adjusted for different lengths of shades. All of these features contribute to a roller shade

support which can be cheaply made and without sacrificing the strength of the support or the durability of the same. It will be obvious 55 that the brackets which support the roller shade are held in engagement with the supports therefor by the weight of the roller shade.

It will readily be seen that with a support 60 such as shown and described above, after it is once attached to a window casing, it does not have to be removed for different size or lengths of shades. The support for the bracket may also be used for supporting curtains, draperies and the like, as more than one supporting bracket can be attached to the support at the same time. One of the important features of my device, therefore, resides in the one common support which may 65 be used for shades, curtains, and draperies, 70 all at the same time.

It is obvious that minor changes in the details of construction may be made without departing from the spirit of the invention as 75 set forth in the appended claim.

Having thus described the invention, what I claim as new and desire to secure by Letters-Patent, is—

A roller shade hanger comprising a sheet 80 metal supporting member adapted to be attached to the window casing, said supporting member being offset between the ends thereof and having pairs of opposed slots formed in its upper and lower edges, a sheet metal bracket having an open recess formed in the rear portion thereof, and a shoulder at the upper side of the recess extending downwardly and partly closing said recess, the distance between the upper and lower sides 85 of the recess being such that when the bracket is attached to the supporting member, the bracket will fit in one of the upper slots, the shoulder engaging said supporting member at the rear face thereof, and the portion of the bracket adjacent the lower edge of the recess will enter the opposed slot at the lower face of the supporting member, said bracket having laterally projecting lugs adapted to bear against the front face 90 of the supporting member for preventing said bracket from swinging laterally.

In testimony whereof, I affix my signature.

WILLIAM L. OWEN.
